UNITED STATES PATENT OFFICE.

MURRAY BACON, OF PHILADELPHIA, PENNSYLVANIA, ASSIGNOR TO THE NOVELTY ELECTRIC COMPANY, OF SAME PLACE.

ELECTRICAL INDICATOR.

SPECIFICATION forming part of Letters Patent No. 324,635, dated August 18, 1885.

Application filed September 15, 1884. (No model.)

To all whom it may concern:

Be it known that I, MURRAY BACON, a citizen of the United States, and a resident of Philadelphia, Pennsylvania, have invented 5 certain Improvements in Electrical Indicators, of which the following is a specification.

My invention consists of an improved electrical indicating apparatus, more especially intended for use on steamers, to indicate in 10 the pilot-house in which direction the engine is running, and whether the signals of the officer in command to the engineer are being properly obeyed. For this purpose I combine with the reversing and throttle-valve levers, or other suitable parts of the valve-gear 15 of the engine, electrical switches connected to the indicator, which is placed in the pilot-house, or wherever it is needed, the switches being operated by the movement of the valve-levers to throw into or out of circuit one or 20 both of two magnets or pairs of magnets, which control a pointer to indicate "ahead," "back," or "stop," or similar signs, according to the position of the switches, due to the movement 25 of the reversing and throttle-valve levers of the engine.

In the accompanying drawings, Figure 1 is a diagram illustrating the circuits and general arrangement of my indicating apparatus. Fig. 30 2 is an outside view of the indicator proper, to be put up in the pilot-house. Fig. 3 is a sectional view of the indicator on the line 1 2, Fig. 4, and Fig. 4 is a vertical transverse section of the same.

Referring to Fig. 1, R is the indicator-box 35 in the pilot-house or other desired point, and L is a rocking arm connected with and operated by the reversing-lever of the engine, while L' is an arm controlled by the operating-40 lever of the throttle-valve.

S is an electrical switch, having a pivoted arm, s, adjustably connected by a link, l, to the arm L, and adapted to make connection with either of two spring-contacts, 1 and 2, 45 according to the position to which the reversing-lever is moved. The arm L' is connected by an adjustable link, l', to the movable arm s' of a switch, S', with a single contact, 3. The contact l of the switch S is connected, through

a conductor, 5, with a pair of electro-magnets, 50 E E, the poles of which face each other, and thence the circuit through a return-wire, 4, containing a battery, M, and the switch S', to the switch-lever s. The contact 2 is similarly connected, through a conductor, 6, to a pair of 55 electro-magnets, E' E', (at right angles to the others,) and thence through the common return-wire 4 to the same switch-lever s.

In each of the two circuits is included an audible signaling device differing from that 60 in the other circuit. Thus in the circuit 5 I have shown an electro-magnetic vibrator, C, with a bell, while in the circuit 6 I have included a "buzzer," B, or vibrator without a bell. 65

Between the poles of the two electro-magnets is an armature, A, which carries or controls a suitable pointer-finger, P. When the throttle-valve of the engine is closed, the lever s' of the switch S' will be free from the contact 70 3 and the circuits through either pair of magnets open, so that the armature A will be unaffected and the pointer hang in the vertical position indicating "stop," Fig. 2; but when the throttle-valve is opened the lever s' will be 75 moved into contact with 3, as shown in the diagram, and the circuit will be closed through one or other pair of magnets, according to the position of the switch-lever s. Thus when the reversing-lever L is thrown over to run the 80 engine backward, as indicated in the diagram, the switch-lever s makes connection with the contact l and the circuit through the electro-magnets E E and "clear" call-bell C is closed. The bell C will ring and the armature A will 85 be attracted to the position indicated in Fig. 1, and the finger P will point to the word "back" on the dial.

When the reversing-lever of the engine is thrown over to go ahead, the lever s will come 90 into contact with 2, to close the circuit through signal B and electro-magnets E' E', which, acting on the armature A, will cause the pointer to be turned to indicate "ahead." It will thus be seen that each movement of the throttle-valve and of the reversing-gear of the engine 95 will be indicated in the pilot-house even before the engine responds.

I prefer to provide the indicator-box with a switch, T, for opening the circuit to save the battery when not needed, as the apparatus may be required only in coming into or going out of port. This switch T is preferably connected with a reversible plate on the indicator-dial, to show the word "Open" when the switch is thrown open.

It will be understood that more than one of these indicators may be included in the circuit, and located at different points on the vessel.

I will now proceed to describe the detailed construction of the indicator-box as illustrated in Figs. 2, 3, and 4.

The case D is preferably of the cylindrical form shown, with dial-plates *d d* on opposite sides having glass fronts *d' d'*. Within the case is a brass frame, F, to which the case is secured, and within the frame are mounted the four electro-magnets E E and E' E', these four electro-magnets forming, in effect, part of the frame, since they connect the front and back plates, *f f'*, of the frame F. These electro-magnets have polar extensions *e e* and *e' e'* projecting inward toward a central point, which is the axis *a* of the armature A. This axis is mounted in bearings in the plates *f f'*, and, projecting through the dial-plates *d d*, carries at its opposite ends the two pointers P.

To one of the plates *f f'*, at one side, is secured the vibrator call-bell C, while to another part of the frame is secured the "buzzer" B; but as these may be of any suitable and well-known construction it will be unnecessary to describe them in detail.

In the dial-plates *d d* are cut curved slots *d' d'*, and behind each dial is a reversible plate, *h*, carried by an axis, H, mounted in bearings in the frame-plates *f f'*, and having a chain pulley or wheel, *h'*, over which passes a manipulating chain or cord, *h''*. By pulling one or other end of this pendent chain or cord the plates *h* may be turned. The axis H also carries the electrical switch T in the return-circuit, and which consists of a contact-arm, *t*, making contact with a spring-finger, *t'*, Fig. 3, in the return-circuit, when the reversible plate is in one position, and with an insulated stop, *t''*, when in the opposite position. On the face of each plate *h* are the words "Ahead," "Stop," "Astern," and "Open." When the axis H is turned to throw the arm *t* into contact with the finger *t'*, the words "Ahead," "Stop," "Back," all show through the curved slot in the dial, as shown in Fig. 2, while

when the plates *h* are reversed to open the circuit the single word "Open" will show through the slot.

The dial-plates are preferably of ground 6c glass or similar material which will allow the letters to be seen at night when a light is arranged inside the case.

On the outside of the case are three binding posts, *p p' p''*, to which the conductors are to 65 be connected, and to which the terminals inside the box are connected; but it has been thought less confusing not to illustrate the circuits in Figs. 3 and 4.

Instead of making the case of the indicator 70 of the form shown and described, it may be of rectangular or other form and only one dial need be employed.

I claim as my invention—

1. The combination of the throttle-valve 75 lever of an engine and an electrical switch operated thereby with an electrical indicator controlled by said switch, substantially as set forth.

2. The combination of the reversing-lever of 80 an engine and an electrical switch controlled thereby with an electrical indicator operated by said switch to show in which direction the engine is running, substantially as set forth.

3. The combination of the valve-lever of an 85 engine and an electrical switch controlled thereby with an indicator consisting of two electro-magnets and an armature, a pointer operated thereby, and a dial, substantially as specified.

4. The combination of a valve-lever of an 90 engine and an electrical switch operated thereby with an indicator consisting of a dial, pointer, and two electro-magnets controlling the pointer, each electro-magnet having an 95 audible signal in circuit differing in character from the other, substantially as described.

5. The combination of the slotted dial-plate and pointer with an axis carrying a reversible sign-plate, and a switch controlled by said 100 axis, substantially as set forth.

6. The combination of the slotted dial-plate with an axis controlling a switch and carrying a reversible sign-plate, a pulley, and a manipulating-chain, substantially as described.

In testimony whereof I have signed my name to this specification in the presence of two subscribing witnesses.

MURRAY BACON.
